UNITED STATES PATENT OFFICE.

ISABELLE MCKEE BLOCH, OF CHICAGO, ILLINOIS, ASSIGNOR TO THE Q R S MUSIC COMPANY, OF CHICAGO, ILLINOIS, A CORPORATION OF ILLINOIS.

INSTRUCTION ROLL.

Application filed June 3, 1922. Serial No. 565,691.

To all whom it may concern:

Be it known that I, ISABELLE MCKEE BLOCH, a citizen of the United States, residing at Chicago, in the county of Cook,

5 State of Illinois, have invented certain new and useful Improvements in Instruction Rolls, of which the following is a specification, reference being had to the accompanying drawings, forming a part thereof.

10 The purpose of this invention is to provide an improved form of perforated note sheet or music roll, so-called, for automatic players, adapted to be utilized in connection with the player for giving musical instruction. It consists in the superficial elements and features shown and described, comprising markings of staff notations and manual interlineations with relation to the perforated area, and to the particular perforations corresponding to the staff notations and manual key interlineations, all as indicated in the claims.

In the drawings:—

Figure 1 shows a portion of a perforated note sheet or music roll, having certain features of this invention.

Figure 2 is a further portion of the same roll which may be understood as immediately following the portion shown in Figure 1, presenting the same feature as shown in Figure 1, as it becomes modified in certain sorts of note combinations.

Figure 3 shows a further portion of the same music roll or note sheet presenting the feature shown in Figure 1 in combination with another feature involving pictorial representation of the manual keys.

Figure 4 shows a further portion of the same roll presenting the additional feature of Figure 3 disassociated from that shown in Figure 1.

Figure 5 may be understood as showing a further portion of the same roll presenting the feature shown in Figure 4 as applied to the black keys of the piano instead of to the white keys.

Figure 6 shows a further part of the roll, incidentally illustrating the roll spool, and presenting the feature of Figure 2 as applied to a scale other than that of the key of C.

The note sheet or music roll, A, has slots or perforations constituting a musical exercise, which, as shown, may consist of the successive notes of a natural or major scale,

of which the slots, 1, 2, 3, 4, 5, etc., are successive along the length of the roll, and progressively offset laterally from each other, according to the advance in pitch. At each of the limited areas containing the respective slots, there is imprinted on the roll a portion of a bar of ordinary staff notation, with the note corresponding to the slot imprinted in its proper place on the staff; and also so that the note imprint is cut by the slot to which it corresponds. And in order that the slots cutting the imprint of the note shall not materially disfigure the latter, or mutilate it so as to render it illegible or of doubtful import, the staff delineation and the notes thereon are magnified very much beyond any usual size of printing music note sheets, and beyond any size which it would be necessary or desirable to employ for ease of reading the same on the music roll. The slots as ordinarily cut in commercial music rolls are from $\frac{1}{20}$ th to $\frac{1}{16}$ th of an inch in width; and the staff notes, of smaller size,—quarter notes and less,—are designed to be made of diameters several times this slot width; and the drawings may be so understood.

Tied and repeated notes, of which the staff markings are necessarily close together and cannot be correctly shown separate or on separate imprints of the staff, are treated as a single note with respect to cutting the area in which they stand by the slot; only, that in this case only one of the slots, and preferably the first one, is made to cut the area allotted to the staff notes. That is, the staff is imprinted so that the staff note character, the imprint of the tied or repeated notes, considered as a single character, is cut by the slot which plays the first of the tied or repeated notes. Instances of such tied or repeated note areas cut by the slot corresponding to the first note of the couple or group are seen at B, B¹, B².

The purpose of the association of the staff note with the slot is partly to cause the definite association of pitch with the position of the note on the staff; which is accomplished by the pupil hearing the note struck while he is looking at the staff notation of it. An analogous purpose is to cause the pupil to associate the pitch of the note struck with the manual key for that purpose; and for this purpose, at a part of the roll, preferably immediately following that

having the staff notation cut by the slot, there are imprinted on the perforated area of the note sheet pictorial representations or delineations of recognizable fragments of 5 a manual of a keyed instrument, as a piano or organ, enough keys being shown in the fragment represented to identify those that appear; that is, the fragment should contain either two black keys with the associated white keys, or three black keys with 10 the associated white keys. And this picture or delineation of the manual key fragments is positioned so that the slot which plays a certain note of the fragment contained in 15 the picture cuts the picture or delineation of the corresponding key. Instances of such pictorial fragments on the manual with the representation of a selected key cut by the slots for playing the corresponding notes are 20 seen at c , c^1 , c^2 , on Figure 4.

With this expedient for associating the manual key with the pitch, it is possible to combine,—and in Figure 3 there is shown a combination—of the expedient illustrated 25 in Figure 1, consisting of the staff notation of the note corresponding to the slot; and this is accomplished by printing the staff notation over the pictorial delineation of the fragment of the manual with the note 30 imprint falling upon the imprint of the corresponding manual key, in which, through which or into which, the corresponding slot is cut. Instances of this combination of the two expedients are shown at C , C^1 , C^2 , on 35 Figure 3. In the employment of the pictorial representation or delineation of a fragment of the manual in association with the slot, or with the slots and the staff notation, tied and repeated notes are treated as unitary characters as to the area occupied by 40 them being cut by the slot, as already described in respect to the repeated and tied notes so cut in Figure 1.

In simple scale exercises the feature last 45 described will commonly necessitate the repetition of the staff imprint for each note, as seen in Figures 1 and 2.

As a matter of instructional convenience, the letter name of the notes may be printed 50 upon the staff notation adjacent to the note imprints respectively, as seen in Figures 4 and 5.

I claim:—

1. A perforated web for controlling the 55 performance of an automatic musical instrument, having imprinted transversely thereon at the perforated area thereof staff notation of certain parts of the music, the characters of the staff notation being printed over the 60 areas proximate to the corresponding perforations, so that said perforations cut through or closely adjacent to the corresponding staff characters respectively.

2. In the construction defined in claim 1, 65 foregoing, the perforated web having suc-

cessively positioned slots for playing respectively the notes of a musical exercise, the staff notation for the respective notes being imprinted at the perforations respectively, with the delineations of the staff lines 70 and clef repeated for each note or group of closely associated notes.

3. In the construction defined in claim 1, foregoing, the characters of the staff notation being of such large dimensions in comparison with the width of the slots as not to be materially disfigured or rendered illegible by the perforations cutting through them. 75

4. In the construction defined in claim 1, foregoing, the staff notes being printed distinguishably with respect to color from the black-line appearance of the slots. 80

5. An instruction roll for utilizing automatic playing devices for teaching manual 85 playing, having imprinted over the areas containing the slots for automatic playing, delineations of significant portions of the manual of the instrument with which the note sheet is designed to co-operate, the slots 90 being cut through the delineation of the keys which correspond to the slots respectively. 95

6. An instruction roll for utilizing automatic playing devices for teaching manual 100 playing, having in combination with the perforate areas thereof, delineations of sections of the manual of the keyed instrument with which the note sheet is desired to co-operate, the slots cutting through the delineations of the keys which correspond to said slots respectively, and the web having imprinted upon the same perforate area across the delineation of the keys, a staff 105 with clef, and with the note corresponding to the key, and to the slot imprinted on said key-delineation. 110

7. An automatic player and note sheet for utilizing automatic playing devices for teaching manual playing, perforated for 115 playing a musical exercise of which the notes at adjacent intervals require length of the note sheet for each note at intervals adequate for imprinting crosswise of the note sheet a staff with clef and having staff 120 and clef so imprinted with the notes corresponding to the respective slots positioned in the width of the sheet in accordance with the pitch and in the length of the sheet in accordance with the time intervals between 125 the striking of the consecutive notes respectively.

8. An automatic player and note sheet for utilizing automatic playing devices for teaching manual playing, of which the respective notes and in their adjacent intervals require length of such notes and interval adequate for imprinting upon the note sheet the recognizable delineation of a section 130 of the manual of a keyed instrument, 135

and having such delineation so imprinted with the keys corresponding to the respective slots positioned so as to be cut by the said slots respectively.

5 9. In the construction defined in claim 5, foregoing, the note sheet having imprinted over the manual key delineation suitable portions of a staff with clef and with the note corresponding to the slot imprinted upon the delineation of the corresponding key.

10. In the construction defined in claim 5, foregoing, the note sheet having imprinted over the manual key delineation suitable portions of a staff with clef and with the letter name of the note corresponding to the slot imprinted upon the delineation of the corresponding key.

In testimony whereof, I have hereunto set my hand at Chicago, Illinois, this 31st day of May, 1922.

ISABELLE McKEE BLOCH.
